(Model.)

H. THOMAS.
PROPELLER SCREW.

No. 438,365.

Patented Oct. 14, 1890.

UNITED STATES PATENT OFFICE.

HERMANN THOMAS, OF NEW YORK, N. Y., ASSIGNOR OF ONE-FOURTH TO
RUDOLPH STUELER, OF SAME PLACE.

PROPELLER-SCREW.

SPECIFICATION forming part of Letters Patent No. 438,365, dated October 14, 1890.

Application filed June 21, 1889. Serial No. 315,064. (Model.)

To all whom it may concern:

Be it known that I, HERMANN THOMAS, of the city, county, and State of New York, a citizen of the Empire of Germany, have invented 5 certain new and useful Improvements in Propeller-Screws, of which the following is a specification.

This invention relates to certain improvements in the construction of screw-propellers 10 for vessels by which a larger working-surface of the blades is obtained and a greatly-reduced quantity of material required for the propeller, so that an increased working power is obtained, and consequently a greater speed 15 imparted to the vessel at a saving of fuel.

The invention consists of a screw-propeller in which each blade is formed of a leading or forward portion and a rear portion, which are united at an obtuse angle with each other, 20 and of which one represents a portion of the cylinder of a screw, while the other represents a thread of the screw, the leading portion cutting or separating the water like a knife, while the rear portion prevents the slipping 25 off of the water, which is equally distributed over the entire surface of the blade. The leading portion of each blade is extended over the hub so as to form a dipping point or wing, which enters into the water in advance 30 of the blade proper. The working-surface of the blade is also increased at the periphery of the same by enlarging the outer ends of the blades and arranging the outer edge in such a manner that every point of the same 35 is equidistant from the axis of the propeller. This effectively enlarges the surface area of the blades and increases the working capacity of the propeller. The hub to which the blades are attached is made of conical shape, its di- 40 ameter at the rear end being larger than the diameter at the front end, so as to provide for the arrangement of the dipping-wings and for retaining the water effectively around the surface of the hub when the propeller is rotated in opposite directions.

In the accompanying drawings, Figure 1 represents a front elevation of my improved screw-propeller. Fig. 2 is a rear elevation of the same. Figs. 3 and 4 are side elevations 45 taken from opposite sides. Fig. 5 shows ver-

tical transverse sections of different forms of the blades, taken on line xx , Fig. 1; and Figs. 6 and 7 are diagrams, illustrating the theoretical development of the blades.

Similar letters of reference indicate corresponding parts.

Referring to the drawings, A represents the hub, and B the blades, of my improved screw-propeller. The blades B are arranged spirally on the hub, the leading or forward portion of each blade being arranged at a greater angle to the axis of the hub than the rear portion of said blade, and each portion having a spiral twist, which constantly increases the angle which each part forms with the axis of rotation as the distance from the hub increases. Each blade is made of a leading portion a and a rear portion b , which are joined to each other at an obtuse angle, as shown in Fig. 5, which angle remains constant throughout the length of the blade. Parts a and b form together an effective working-surface, the rear portion representing a portion of the cylinder of a screw while the leading portion represents the thread of a screw. The leading portion a cuts or separates the water like a knife and in the same manner as the thread of a screw, while the body of water which is cut by the same is prevented from slipping off by the rear part.

By the angle formed by the two portions a and b of the blade the water is retained and equally distributed over the entire surface of the blade. The friction of the water on the working-surfaces of the blades is equalized as much as possible, as the surfaces of the blades in the direction in which the water is cut are circular, and as they are jointed at all points at the same angle, whereby a reaction of the water is made impossible and an easier and more effective working of the propeller produced.

The leading portion of each blade is extended inwardly and forwardly over the hub A, so as to form a wing d , which enters into the water in advance of the leading portion of the blade, and by which the blade is enlarged at or near the hub, where the greatest working effect is produced. The width of the blade is also increased at its outer end, as the

leading and rear portions *a* and *b* are continued nearly at their full width to the periphery of the blade, which periphery is so constructed that each point thereof is equi-distant from the axis of the screw. The working capacity of the blades is thereby greatly enhanced, owing to the increase in the working-surface of the blade, which is an essential advantage that is not found in any other screw-propeller, and by which the screw-propeller is enabled to exert a greater propelling power. The enlargement of the blades by the dipping wings at the hub and by the widening of the blades at the periphery has also the advantage of reducing the vibrations of the vessel caused by the oscillations of the screw-propellers, inasmuch as the propeller is subjected by the easy cutting through the water and the close hugging of the latter to the working-surfaces of the blades to a smaller amount of injurious strains and interfering influences. The dipping wings on the hub also have the advantage that the main part of the work which the propeller has to perform is accomplished in close proximity to the propeller-shaft, while the enlarged size of the blades at the periphery counterbalances the enlargement produced by the wings. The greatest width of the blades is arranged at mid-length of the same, from which their width is slightly decreased toward the periphery. The obtusely-angled cross-section of the blades also gives a longer surface-connection with the hub and increases the strength and resistance of the entire propeller to the water, as the front and rear parts of each blade strengthen each other, which gives to the blade a great advantage for towing as well as for speed purposes. The blades may be riveted or otherwise fastened to the hub, so that each blade can be removed and replaced by another or cast integral with the hub, as desired.

The hub *A*, to which the blades are attached, is of conical shape and diminishes in size from its rear toward the forward end, so as to arrange for the forward-extending dipping-wings and the proper connection of the same with the hub. The conical shape of the hub also facilitates the retention of the water on the surface of the hub when the propeller is rotated in opposite direction for backing the vessel.

Having thus described my invention, I claim as new and desire to secure by Letters Patent—

1. A screw-propeller having blades of obtusely-angled cross-section, said blades being extended at their inner front ends over the hub so as to form dipping wings, substantially as set forth. 60

2. A screw-propeller having blades arranged spirally on the hub, the leading or forward portion of each blade being arranged at a greater angle to the axis of the hub than the rear portion of said blade, and the front or cutting edge of each blade being inclined spirally rearward from the front of the hub, all substantially as described. 65

3. A screw-propeller having blades whose front or leading portion is united to the rear portion thereof at an obtuse angle, which angle remains constant throughout the length of the blade, the leading portion being arranged at a greater angle to the axis of the hub than the rear portion thereof and each portion having a spiral twist, which constantly increases the angle which each part forms with the axis of rotation as the distance from the hub increases, substantially as described. 70 75

4. A screw-propeller the blades of which are arranged spirally on the hub and formed of two portions which are united at an obtuse angle to each other, the leading portion of each blade being extended over the hub at its inner end and the rear portion enlarged toward the periphery, so that the width of each blade at the periphery is somewhat smaller than the width of the blade at its center, whereby the working-surfaces of the blade are enlarged toward the hub and periphery, 80 85 90 substantially as set forth.

5. A screw-propeller composed of a conically-tapering hub and of obtusely-angled blades extending from said hub, substantially as set forth. 95

6. A screw-propeller having obtusely-angled blades arranged spirally on the hub, the leading portion of each blade being arranged at a greater angle to the axis of the hub than the rear portion of said blade and extended at its inner end over the hub so as to form dipping wings, substantially as set forth. 100

In testimony that I claim the foregoing as my invention I have signed my name in presence of two subscribing witnesses.

HERMANN THOMAS.
